ROTARY MOLDING MACHINE FOR BISCUIT DOUGH

Filed Nov. 30, 1944

UNITED STATES PATENT OFFICE

2,480,505

ROTARY MOLDING MACHINE FOR BISCUIT DOUGH

John Currie Paterson, Ovenden, Halifax, England

Application November 30, 1944, Serial No. 565,944
In Great Britain December 2, 1943

1 Claim. (Cl. 107—8)

1

This invention relates to rotary moulding machines for biscuit doughs and the like of the type wherein an endless web running over a knife edge for delivery purposes passes into arcuate contact with the die roll and is pressed into contact therewith by a resilient extraction roll.

An object of the present invention is to provide improvements adapted to facilitate the extraction of the dough shapes from the die roll cavities without damage or undue distortion of the dough shapes and without subjecting the extracting web to undue wear.

Present-day arrangements are open to the objection that the necessary tensioning of the web has been effected upon the driving side (i. e. the return run) of the web. In this arrangement the resistance offered by the knife edge means that in order to maintain the web taut (particularly at the part where it leaves the pressure or driving roll) undue strain has to be put upon the web with a consequent shortening of its life, and an aim of the present invention is to avoid the above objection and provide an arrangement whereby adequate tension may be maintained upon the web, including the part where it leaves the pressure or driving roll and runs in arcuate contact with the die roll, without subjecting the web to excessive strain and unnecessary wear.

Another object is to avoid the objectionable feature of tension applied by screw means, whereby when a web is dry, say when new or after a weekend or other period when it is not in use, sufficient tension is given to it to ensure drive without slip, but as the web soaks up moisture from the dough it shrinks and thus increases its tension causing damage by tearing or shortening of its width.

According to the invention tension is applied to the slack (or upper run of the web) by an automatically operating means such as a gravity actuated web deflecting device adapted to position the web with respect to the die roll and maintain a substantially constant tension upon the web.

The invention also consists in a deflecting device in the form of a jockey roll applied to the underside of the upper run of the web and positioned adjacent the die roll and having counterweight or equivalent means whereby the jockey exerts a substantially constant deflecting pressure against the web and maintains it in appropriate tension.

According to one arrangement the jockey roll is positioned to maintain a portion of the web in substantial arcuate contact with the die roll and

2

the mounting of the jockey is such that it has an automatic floating pressure action against the web, the loading pressure being dependent upon the adjustment of the counterweight.

5 5 The accompanying drawing shows a side elevation of a machine according to the invention.

In carrying the invention into effect according to one mode as described by way of example, an endless web 2 is mounted so that it laps around 10 the resilient pressure and extracting roll 3 of the rotary moulding machine comprising a feed roll 4 and a die roll 5 mounted to rotate on horizontal axes and to which dough is fed from a hopper (not shown). The web 2 passes through 15 the nip between the die or moulding roll 5 and the pressure roll 3. A drive to the web 2 is imparted by the pressure roll. The delivery end of the web 2 is passed over the usual knife edge 6 which may be fixed or longitudinally adjustable. 20 If desired, adjacent the knife edge, a tracking roller 7 may be positioned in contact with the underside of the upper run 2a of the web 2 for the purpose of adjusting any tendency for irregular tracking of the web.

25 Between the die roll 5 and the knife edge 6 the web 2 passes over a jockey roll 8 the axis of which is parallel with that of the die roll 5. The jockey roll 8 is mounted upon a pair of side levers 9 which are pivoted on a fulcrum axis parallel

30 with that of the jockey roll. The levers 9 extend beyond their pivotal axis and each is adapted to receive a balance or counterweight 10 the position of which on the levers may be varied in order to adjust the loading of the jockey roll 8 or, alternatively, the counterweight may be in 35 the form of a plurality of separate detachable weights.

The fulcrum 11 of the jockey roll levers 9 is positioned so that the roll 8 lies adjacent to the die roll 5 with a view to deflecting the web 2 from the point where it issues from the nip to cause it to pass in a substantial arcuate contact with the lower part of the die roll surface.

40 The return run 2b of the web 2 travels over a guide roll 12 which may be conveniently located co-axially with the fulcrum 11 of the jockey roll levers.

Between this guide roll 12 and the knife edge 6 a scraper 13 may be positioned for contact 50 with the underside of the return run 2b of the web and below the scraper a waste hopper 14 may be provided so that the scrapings from the web may be conveniently collected and discharged from time to time.

Between the jockey roll 8 and the tracking

roll 7 or knife edge 6 the extracting web 2 requires no support and may run in an unsupported condition, although a supporting means may be provided if desired.

The jockey roll 8 should preferably be of substantial diameter, for example a suitable diameter has been found to be about six inches. If a jockey roll of too small a diameter is used there is liability to break the biscuit shapes while they are being carried by the extracting web 2 over the curvature of the jockey roll. The jockey roll 8 may conveniently be mounted upon its levers in a readily detachable manner. For example, the ends of the levers may have transverse slots 15 in which the ends of the shaft or trunnions 16 of the jockey roll may be located so that the roll may be readily lifted out of the slots for any purpose.

The jockey roll 8 and counterweight 10 may be out of balance to an extent suitable to cause the jockey roll to press upwardly upon the underside of the web 2 to hold the web in arcuate contact with the die roll 5 and provide the appropriate tension. Dough is supplied to the rolls 4 and 5 by a hopper mounted above said rolls.

The web 2 delivers the biscuit shapes to an oven band 17 or other receiving surface.

In operation, it will be appreciated that owing to the mounting of the jockey roll 8 on the counter-weighted levers 9 it possesses an automatic or self-adjusting floating action against the underside of the web 2 and maintains a substantially constant tension.

The bearings for the various rolls are located on side frames 18 of the machine and the rolls 3, 4, 5 are driven in the appropriate direction and

at the desired speeds by trains of gears from a suitable prime mover in known manner.

I claim:

A rotary biscuit moulding machine of the type described comprising a die roll, an endless web travelling over a knife edge and a resilient extraction roll and pressed into contact with the die roll by the extraction roll, said web having an upper run contacting with an arcuate portion of the die roll, automatically adjustable means applied to the underside of said run adjacent the position where the web leaves the die roll whereby the web is automatically maintained in arcuate contact with the die roll and stretching and shrinking of the web is automatically accommodated, and including counterweighted levers, a jockey roll supported in said counterweighted levers to exert a substantially constant deflecting pressure against the web and a guide roll located on the pivotal axis of said levers for guiding the return run of the web.
